By

Hardway, Cactus
Attorney

UNITED STATES PATENT OFFICE.

HENRY S. McGARRY, OF HOUSTON, TEXAS.

SLIP.

Application filed November 1, 1923. Serial No. 672,216.

To all whom it may concern:

Be it known that I, HENRY S. McGARRY, a citizen of the United States, residing at Houston, in the county of Harris and State 5 of Texas, have invented certain new and useful Improvements in a Slip, of which the following is a specification.

This invention relates to new and useful improvements in a slip.

One object of the invention is to provide 10 a slip, or pipe holder, specially designed for holding pipe suspended in a rotary table or casing head, and so constructed that it will so securely grip the pipe that there will be 15 no danger of dropping the pipe in the bore. When used in connection with a casing head, the slips are of a design and size to readily engage with pump tubing, and the like, to hold the same while the tubing is being withdrawn 20 from or let down into the casing.

Another object of the invention is to provide 25 a pipe engaging slip having independent jaws so secured together that each jaw will engage with the pipe, and in case the pipe is out of round or irregular in shape the jaws will adjust themselves to the contour of the pipe and engage with it all the way around.

A further feature of the invention resides 30 in the provision of a slip composed of a plurality of sections, each section having a plurality of pipe engaging jaws, so secured together that they will be securely held in place, and in position to engage with the pipe, and cannot turn around, or rotate on their vertical axes, as is the case with certain slips now in common use.

A still further feature of the invention resides 35 in the provision of a sectional slip, each section being provided with a novel type of handle which is so constructed that when not in use it will lie in horizontal position out of the way of the workmen and in such position it will be protected against becoming accidentally broken off.

The slip herein described is also comparatively 40 light, and of very simple construction, and can be cheaply produced and easily handled.

With the above and other objects in view, 45 this invention has particular relation to certain novel features of construction, operation and arrangement of parts, an example of which is given in this specification, and

illustrated in the accompanying drawings, 55 wherein:—

Figure 1 shows a plan view of the slip, showing the handles partly broken away.

Figure 2 shows an inside view of one of the sections; and,

Figure 3 shows a transverse sectional view taken on the line 3—3 of Figure 2.

Referring now more particularly to the drawings, wherein like numerals of reference designate similar parts in each of the figures the numerals 1 and 2 designate the upper and lower keeper plates, respectively, of each section of the slip. These plates are arcuate and are held in spaced relation by means of the bolts 3, 3, which are fitted upwardly through the lower plate and whose upper ends are threaded through the corresponding upper plate. The lower plate is sustained by the heads of said bolts, and the bolts are of a length to space said plates the proper distance apart. The facing sides of said plates are arcuately grooved, thus providing the arcuate mortises 4 and 5. Each section of the slip will have a plurality of pipe engaging jaws, as 6, preferably three 80 in number. Each jaw consists of an arcuate segment of the complete slip, and tapers downwardly. The inner surface of each jaw is toothed to provide a pipe engaging surface. The ends of the jaws have projecting, 85 arcuate tenons, as 7 and 8, designed to fit loosely in the respective mortises 4 and 5.

The bolts 3 are fitted between jaws of each section, the adjacent edges of said jaws being grooved lengthwise, as at 9, to provide suitable bearings, between them, to receive said bolts.

The slip may be composed of two or more sections, two only being preferred.

The complete slip tapers downwardly, as 90 shown, so as to fit in the conventional seat in the rotary table or casing head, and wedge around the pipe therein.

Each section of the slip is provided with a suitable handle by means of which it may 100 be readily handled by the workmen. This handle consists of the rod 10 whose outer end is formed into a hand grip 11. The other end of the handle is pivoted between the lugs 12, 12, formed integrally with, and 105 upstanding from, each plate 1. The outer sides of these lugs are beveled upwardly toward each other. When the slip is in use,

and in engagement around the pipe, the handles 11 lie back in approximately a horizontal position, and will in a great measure be protected by said lugs from heavy objects 5 falling on the rotary table. It is common practice to break up the pipe into sections by the use of the rotary in withdrawing a string of pipe from the bore, and to make up the string with the rotary in letting the 10 string of pipe down into the bore. This operation is well known to those familiar with drilling by the rotary process, and in doing this work, the slips are in place around the pipe, not only to hold the pipe suspended in 15 the bore, but also to rotate the same. In accomplishing this work, a tong is applied to the pipe above the rotary, and it often happens, in starting the rotary, the tong will drop down onto the rotary table, and yet 20 remain in engagement with the pipe, and will consequently be revolved around with the table. In such case the tong jaws will be guided up over the handle by the inclined outer faces of the lugs 12, and injury to, and 25 the breaking of the section handles is thus avoided.

What I claim is:

1. A pipe holding slip comprising a plurality of sections, each section including an 30 upper and a lower plate, a plurality of pipe engaging jaws between said plates which articulate therewith, the articulating faces being formed, one with a mortise and the other with a tenon, which fits into said 35 mortise, and means holding said plates in fixed relation.
2. A pipe holding slip comprising a plurality of sections, each section including an upper and a lower plate, jaws between said 40 plates, one of said plates having an arcuate mortise, tenons carried by said jaws and fitting into said mortise, and means holding said plates in fixed relation.
3. A pipe holding slip comprising a plurality of sections, each section including a cage-like holder, a plurality of jaws in each holder, end tenons formed on the jaws, said holder having mortises in which the tenons fit.
4. A pipe holding slip comprising a plurality of sections, each section including arcuate end plates, independent jaws between 50 said plates whose facing sides are length-

wise grooved to form bearings, and rods in said bearings whose respective ends are 55 attached to said plates.

5. A pipe holding slip comprising a plurality of sections, each section including a cage-like holder, a plurality of jaws in each holder, end tenons formed on the jaws, said 60 holder having mortises in which the tenons fit, the adjacent faces of said jaws having lengthwise grooves forming bearings, and said holder including rods which are fitted through said bearings.

6. A pipe holder including a plurality of sections, each section being composed of upper and lower end plates, independent jaws between said plates, spaced lugs carried by the upper plate of each section, the outer 70 sides of said lugs being beveled upwardly toward each other, and a handle for each section pivoted at one end, between the lugs thereof.

7. A pipe holder including a plurality 75 of sections, each section including an upper and a lower end plate, a pair of spaced lugs upstanding from the upper plate, a handle pivoted at one end between the lugs, independent pipe engaging jaws between 80 said plates.

8. A pipe holder including a plurality of sections, each section including an upper and a lower end plate, a pair of spaced lugs upstanding from the upper plate, a 85 handle pivoted at one end between the lugs, independent pipe engaging jaws between said plates, and means holding said plates in fixed relation.

9. A pipe holding slip comprising a plurality of sections, each section including an upper and a lower end plate, a plurality of pipe engaging jaws between said plates which articulate therewith, the articulating parts being formed, one with a mortise and 95 the other with a tenon which fits into said mortise, means holding said plates in fixed relation, and means for moving each section as a unit.

In testimony whereof I have signed my 100 name to this specification in the presence of two subscribing witnesses.

HENRY S. McGARRY.
